SCALP PROTECTOR

Rudy A. Satrian, Chattanooga, Tenn.

Substituted for abandoned application Serial No. 261,333, March 11, 1939. This application October 21, 1946, Serial No. 704,786

6 Claims. (Cl. 132—36.1)

1

This invention relates to improvements in accessories used in connection with the permanent waving of hair and pertains particularly to an improved scalp protector or spacer. In the operation of permanent waving, the hair is secured between two jaw members which are placed against the scalp and these jaw members are secured firmly together and support a rotatable cylinder on which the hair is wound. In the device at present in use, the separable ends of the jaws are secured together by a cross connecting lock and the cylinder on which the hair is wound and which includes a pawl and a spring ratchet mounted upon one of the jaws, is so supported that it is necessary for the operator to employ both hands in taking out the roller.

The present invention has for its primary object to provide an improved coupling means between the hair gripping jaws whereby the said jaws of the spacer may be readily separated with one hand and an additional feature of the present device resides in the novel construction of the supporting means for one end of the roller whereby such supporting means releases the roller automatically when the jaws are separated.

Another object of the invention is to provide an improved spacer or hair securing clamp wherein the operating means for securing the jaws in clamped relation or for releasing the jaws, is disposed at one side of the spacer in such a manner that the operator may hold the spacer between a thumb and finger of the hand and employ another finger of the same hand to release the jaws and shift them into separated position, in which position the roller on which the hair is wound will be automatically released.

The invention will be best understood from a consideration of the following detailed description taken in connection with the accompanying drawing forming part of this specification, with the understanding, however, that the invention is not to be confined to any strict conformity with the showing of the drawings but may be changed or modified so long as such changes or modifications mark no material departure from the salient features of the invention as expressed in the appended claims.

In the drawing:

Fig. 1 is a view in top plan of the protector embodying the present invention;

Fig. 2 is a view in top plan of the device with the jaws separated and cylinder removed;

Fig. 3 is a view in end elevation of the device with a portion broken away;

2

Fig. 4 is an end view illustrating the separable trunnion bearing; and

Fig. 5 is a side view of the device at the pivoted ends of the jaws.

Referring now more particularly to the drawing, the numeral 1 generally designates the spacer device or clamp for the hair while the numeral 2 designates the cylinder which is rotatably mounted upon the spacer and upon which the hair is wound.

The spacer 1 comprises the two usual jaw members 3 and 4, each of which consists of a flat strip of metal which has one edge and the top and bottom faces thereof covered by a rubber guard 5.

In accordance with the present invention, one of the jaw members, for example, the jaw 3, is formed at one end with the laterally extending arm 6, while the opposite jaw has the end adjacent the arm 6 laterally and obliquely extended to form the lever arm 7. The end of the arm 6 of the jaw 3 is pivotally attached to the jaw 4 at the inner end of the lever arm 7, as indicated at 8.

25 The jaws 3 and 4 at their opposite ends have upturned portions 9 and 10, respectively, which, when the jaws are in hair gripping relation, are brought into edge opposed relation, as shown in Figure 3, and as is also shown in this figure, one of these upturned portions is recessed at its top and adjacent the inner edge thereof to form a bearing 11, while the adjacent or opposed upturned portion 10 extends across and forms one side of the bearing. As is also clearly shown in

30 this figure, one of the upstanding end portions is provided with a tongue 12 which extends into a receiving slot 13 in the opposing portion, thus forming an interlocking connection between the free ends of the jaws which, when the jaws are closed, holds them in aligned relation. One of the jaw members, here illustrated as jaw 3, has pivotally attached thereto at the end remote from the arm 6, one end of a lever bar 14, the other end of this bar being formed to provide the

35 upstanding finger piece 15. Pivotally attached to the lever bar 14 adjacent the free end thereof is one end of a link 16, the other end of this link being pivotally connected, as indicated at 17, to the free end of the lever arm 7.

40 When the jaws 3 and 4 are in aligned relation, the arm 7 of the jaw 4, which jaw may be referred to as the movable jaw, extends across the adjacent end of the other or fixed jaw 3 and away from the latter, and the bar and link 45 14—16 are in parallel relation with one another.

and with the adjacent jaw 3. By bringing the bar and link into this parallel relation, the jaws are firmly secured together and the upturned end portions 9 and 10 are in the interlocked relation shown in Figure 3.

Formed integral with the edge of the arm 6 remote from the jaw 3, is an upstanding flange 13, the top edge of which is provided with a bearing notch 19. This bearing notch is aligned longitudinally of the device with the bearing recess 11, when the jaws are in gripping relation, and the bearing notch and recess are designed to receive the trunnion-like ends 20 and 21, respectively, of the cylinder 2. This cylinder is of the usual construction in that it comprises the elongated jaw portion 22 which is enlarged at each end and at one end is formed to provide the encircling ratchet 23 which is designed to be engaged by the spring pawl 24 which is supported upon one of the jaw members, preferably the movable jaw 4, as shown. The trunnion 20 which engages in the bearing notch 19, has formed integral therewith the key head 25, by which the turning of the cylinder is facilitated, and the cylinder also carries the usual pivotally attached finger 26, which secures the ends of the hair against the cylinder when starting the operation of winding the hair on the cylinder.

From the foregoing, it will be readily apparent that in the present spacer device or scalp protector, the opening or closing action of the jaws may be readily accomplished by the use of one hand and that when the jaws are opened by shifting the lever bar outwardly away from the adjacent body so as to effect the swinging of the other or movable jaw, away from the body 3, the bearing support for the end of the cylinder which is engaged by the spring pawl 24, will be opened or separated so that said end of the cylinder will be separated from the spring pawl and the cylinder may be lifted out without requiring that the operator manipulate the spring pawl to disengage it from the ratchet 23.

As previously stated, the devices which are at present in use are so constructed that both hands must be employed for removing the spring pawl engaged end of the cylinder as it is necessary to hold the cylinder with one hand and force the spring pawl free from the cylinder with the other hand. With the present device, this is not necessary, as the mere separation of the free or unconnected ends of the jaws simultaneously disengages the cylinder from the spring pawl.

The lever mechanism connecting the jaws together and consisting of the arm 6, bar 14 and link 16, is so designed that when the jaws are in closed position, they will be firmly secured together as the link 16 and the lever bar 14 are then in aligned relation and are exerting the maximum force against the free end of the lever arm 7 necessary to hold the jaws tightly together in gripping relation.

This application is a substitute for my application Serial No. 261,333, filed March 11, 1939, and abandoned.

What is claimed is:

1. In a scalp protector of the character described, a pair of jaw members adapted to be brought into parallel gripping relation, means pivotally coupling said jaws together at one end of the device, an arm integral with one of said jaws at the said pivotally connected ends and extending at an obtuse angle with respect to and across the adjacent jaw, a lever bar pivotally attached to one side of the said adjacent jaw, a link

pivots coupling said bar with the free end of said arm, said bar and link when in aligned relation operating upon said arm to hold said jaws in parallel relation, and means at the ends of said

5 device for rotatably supporting a hair winding cylinder, said means comprising at one end of the device, two separable members each carried by a jaw and cooperating to form a bearing for the support of the adjacent end of the cylinder.

10 2. In a scalp protector of the character described, a pair of elongated jaw members adapted to be disposed in side by side relation, means pivotally coupling said jaw members together at the two adjacent ends thereof, the opposite ends 15 of the jaw members being free and designed to be swung apart, means disposed adjacent to the outer longitudinal side of one jaw member and operatively coupling the free end thereof with the other jaw member at the pivoted end of the latter for actuating and locking the said jaws into 20 closed gripping relation, a hair winding cylinder designed to be disposed longitudinally of the jaws and having supporting trunnions at its ends, and means forming a supporting bearing at each end 25 of the device for engagement with a trunnion of the cylinder, the said supporting bearing at the said free ends of the jaws being divided into two portions each of which is carried by a jaw member.

30 3. A scalp protector of the character described, comprising a pair of elongated jaw members adapted to be disposed in edge to edge relation, an arm formed integral with one jaw member at one end thereof and extending across the opposite 35 jaw member and pivotally attached thereto, a lever arm integral with the said opposite jaw member and extending from the pivoted end thereof at an obtuse angle therefrom and across the end of the adjacent jaw, a lever bar pivotally attached at one end to the first mentioned jaw at the end remote from the arm carried thereby, a link pivotally connected between said lever bar and the free end of the lever arm, said link and lever bar being adapted to assume a parallel 40 relation in which the lever arm carrying jaw is moved into parallel relation with the first mentioned jaw, a hair winding cylinder adapted to be disposed longitudinally of the protector and having a longitudinal trunnion at each end, and 45 bearing means at the ends of the spacer for rotatably receiving said trunnions, the bearing means at the ends of the jaws remote from the pivoted arm being in two separable portions each of which is carried by a jaw.

50 4. A scalp protector of the character described, comprising a pair of elongated jaw members adapted to be disposed in edge to edge relation, an arm formed integral with one jaw member at one end thereof and extending across the opposite 55 jaw member and pivotally attached thereto, a lever arm integral with the said opposite jaw member and extending from the pivoted end thereof at an obtuse angle therefrom and across the end of the adjacent jaw, a lever bar pivotally 60 attached at one end to the first mentioned jaw at the end remote from the arm carried thereby, a link pivotally connected between said lever bar and the free end of the lever arm, said link and lever bar being adapted to assume a parallel relation in which the lever arm carrying body is moved into parallel relation with the first mentioned jaw, a hair winding cylinder adapted to be disposed longitudinally of the protector and having a longitudinal trunnion at each end and bearing 65 means at the ends of the spacer for rotatably 70 means at the ends of the jaws remote from the pivoted arm being in two separable portions each of which is carried by a jaw.

receiving said trunnions, the bearing means at the pivotally connected ends of the jaws comprising an integral upstanding portion of said first arm and having a trunnion receiving notch in its top, edge and at the opposite end of the spacer comprising two separable portions each forming an upturned part of a jaw.

5. A scalp protector of the character described, comprising two elongated jaw members designed to be disposed in side by side relation, means pivotally coupling said jaw members together at two adjacent ends thereof, means disposed at the outer longitudinal side of one jaw member and operatively coupling the said one jaw member at the end thereof remote from said pivotal connection with the end of the other jaw member adjacent the pivotal connection for oscillating the jaws into or out of gripping relation, a hair winding cylinder adapted to be disposed longitudinally of the protector, said cylinder having a longitudinal trunnion at each end and a ratchet encircling one end, means carried by one jaw at the pivoted end thereof forming a trunnion supporting bearing, means carried by each jaw at the end remote from the pivot and coupled to form a separable bearing for the other trunnion, and a spring pawl secured to the jaw opposite said lever bar for engagement with said ratchet.

6. In a scalp protector of the character de-

scribed, a pair of jaw members adapted to be brought into parallel gripping relation, means pivotally coupling said jaws together at one end of the device, an arm integral with one of said jaws at the said pivotally connected end and extending at an obtuse angle with respect to and across the end of the adjacent jaw, a lever bar pivotally attached to one side of said adjacent jaw, a link pivotally coupling said bar with the free end of said arm, said bar and link being oscillatable into an aligned relation for effecting application of thrust in a direction to swing the said one of the jaws to a position parallel with the said adjacent jaw and secure the jaws in the said parallel relation, and means for rotatably supporting a hair winding cylinder.
